UNITED STATES PATENT OFFICE

OTTO GREGAREK, OF PHILADELPHIA, PENNSYLVANIA

COMBINED HEEL AND ARCH SUPPORT

Application filed April 21, 1930. Serial No. 445,847.

My invention relates to new and useful improvements in a combined heel and arch support and has for its object to so construct a device of this kind that the arch support 5 will be a continuation of the heel and be permanent parts of each other.

A further object of the invention is to so fashion and construct or manufacture the device that it may be entirely of felt or other 10 suitable material preferably a compressible material so as to provide a certain amount of resiliency and which when in use will develop the proper medial tread, namely, a tread from the center of the heel on a straight 15 line forward through the great toe, thus bringing the bones of the foot in proper alignment and give the effective support to the arch.

A further object of the invention is to provide a support of this kind wherein an especially thick portion is provided for supporting the cuboid bone.

A still further object of the invention is to provide a combined heel and arch support 25 having a unique outline or configuration and fashioned to provide inclined portions leading to the edges thereof.

With these ends in view, this invention consists in the details of construction and combination of elements hereinafter set forth and then specifically designated by the claims.

In order that those skilled in the art to which this invention appertains may understand how to make and use the same, I will 35 describe its construction in detail, referring by numerals to the accompanying drawings forming a part of this application, in which:—

Fig. 1 is a top plan view of my combined 40 heel and arch support showing a skeleton foot in broken lines in proper relative position to the device.

Fig. 2 is an edge view thereof looking in the direction of the arrow adjacent Fig. 1.

Fig. 3 is a section on the line 3—3 of Fig. 1.

In carrying out my invention as herein embodied, 5 represents a combined heel and arch support consisting primarily of the heel element 6 and the arch support or supporting

element 7, the latter in particular being of unique outline or configuration and embodying a concave exterior side edge 8, a generally convex forward edge 9 and concave interior edge 10. From the interior edge or upon that side on which the great toe falls projects an extension 11 so as to underlie the first metatarsal bone of the foot while from the edge upon which the small toe falls or from the exterior edge is formed a projection 12 which underlies the fifth metatarsal bone and said side edges, front edge and extensions are skived inwardly and upwardly on the top face of the device and more particularly the supporting element. 55

The device has the exterior side in the region where the cuboid bone rests thereon slit as indicated at 13 and a wedge 14 of the same material as the balance of the device is inserted and then fixed in place by stitches 60 15 or other suitable fastening means. 65

As plainly shown in Fig. 3, an enlargement 17 is thus produced and the thicker part of the wedge is at the edge of the device and as will be obvious by reference to Fig. 2, the 70 sides of said wedge are tapered, therefore an enlargement is provided on the device which inclines from the interior edges inwardly toward the center of the device although terminating short of the longitudinal center and also inclines sidewise relative to the enlargement but forwardly and rearwardly relative to the device as a whole. 75

From the foregoing description it will be readily seen that the rear joints of the bone of the arch will be supported on the inclined surfaces at the interior and exterior sides of the supporting element while the enlargement formed by the wedge 14 will support the cuboid bone while the other bones of the posterior arch will be supported in proper position by the blending of the skived side edges with the heel element. 80 85

The forward bones of the foot are supported in proper positions and relation to one another by the skiving along the forward edge in conjunction with the extension 11 and 12 and the blending of the skiving along the forward edge and the skiving along the interior edge provides a ridge 16 to extend be- 90 95 100

tween the joint of the great toe and the joint of the next toe so as to properly position these joints and prevent crowding which is essential to maintain the proper tread.

5 A support constructed as herein described will not only develop the proper medial tread from the center of the heel on a straight line forward to the great toe but will also cause the anterior and posterior arches to assume 10 natural positions, and will also support the cuboid bone and prevent undue strain on the longitudinal arch thereby tending to maintain the foot as a whole in a natural position.

The device being made entirely of felt, 15 preferably, provides a soft and yielding tread to the foot, gives a sufficient support to the arch and avoids any hard pressure upon the under side of the bone of the foot; and being resilient, it will take up perspiration 20 and give sufficient ventilation to the foot to prevent disagreeable odors and the formation of callouses. A combined heel or heel pad and arch support manufactured as set forth herein will be light in weight and may 25 be readily removed for cleansing and airing.

Of course I do not wish to be limited to the exact details of construction as herein shown, as these may be varied within the limits of the appended claims without departing from the spirit of my invention.

Having thus fully described my invention, what I claim as new and useful is:—

1. A device of the kind described consisting of a heel element, an arch supporting element formed integral with the heel element and fashioned to provide concaved side edges and a convex forward edge, an extension projecting from the forward part of the exterior edge to underlie the fifth metatarsal bone, 35 another extension projecting from the interior side adjacent the forward end to underlie the first metatarsal bone, all of said edges and the extensions being skived to form inwardly and upwardly inclined surfaces, and 40 a ridge formed by the meeting of the forward and interior side skivings, said ridge adapted to lie between the great and second toe.

2. The structure set forth in claim 1 in combination with a wedge having tapering side edges inserted in a slit in the exterior side edge of the device in the region of the position occupied by the cuboid bone of the foot.

In testimony whereof, I have hereunto affixed my signature.

OTTO GREGAREK.
